PANEL METER

Roger B. Kerr, Marblehead, Mass., assignor to General Electric Company, a corporation of New York

Filed Dec. 22, 1960, Ser. No. 63,307

Term of patent 14 years

(Cl. D52—6)

FIG.1

FIG.2

FIG.3

FIG. 1 is a perspective view of a panel meter, showing my new design;

FIG. 2 is a front elevational view thereof; and

FIG. 3 is an enlarged sectional view thereof along line 3—3 of FIG. 2 showing the concentric grooves of the rear of the transparent face of the meter.

The dominant features of my new design are shown in solid lines in the drawings.

The characteristic feature of the design resides in the concentric grooves on the inner surface of the projecting glass covering the dial face.

I claim:

The ornamental design for a panel meter, as shown and described.
